UNITED STATES PATENT OFFICE.

EDGAR H. LUSHER, OF PORTLAND, OREGON.

RAZOR HOLDER.

Application filed May 28, 1924. Serial No. 716,408.

To all whom it may concern:

Be it hereby known that I, EDGAR H. LUSHER, a citizen of the United States, and a resident of Portland, in the county of 5 Multnomah and State of Oregon, have invented a new and useful Razor Holder, of which the following is a specification.

This invention relates generally to the tonsorial art, and particularly to means for 10 holding blades of safety razors while sharpening same on an ordinary strop.

An object of my invention is to provide an exceedingly simple and efficient holder for 15 all kinds of safety razor blades while sharpening on an ordinary razor strop.

A second object is to provide a wooden holder which will be light in weight, easy to manufacture and easily kept clean.

A third object is to so construct same that 20 the blades can be securely held and easily inserted or released from the holder.

A fourth object is to so construct the device that both thick and thin blades may be held without injuring the cutting edge 25 which may accidentally come in contact with the holder.

A fifth object is to so construct the holder that it cannot injure the strop.

I accomplish these results in the manner 30 set forth in the following specification and illustrated in the accompanying drawing, in which:

Figure 1 is a side elevation of my device showing it holding an ordinary two-edge 35 wafer blade. Figure 2 is a plan of Figure 1. Figure 3 is a section taken along the line 3—3 in Figure 1. Figure 4 is a section taken along the line 4—4 in Figure 3. Figure 5 is a section taken along the line 5—5 40 in Figure 3. Figure 6 is a section taken along the line 6—6 in Figure 3.

Similar numbers of reference refer to the same parts throughout the several views.

Referring in detail to the drawing, I have 45 constructed my device of two wooden handle members 10 and 11 whose ends 12 are provided with recesses 13 to receive the back of a concave blade 14.

A rivet 15 passes through both members 50 10 and 11 and unites them into a solid handle. A dowel pin 16 passes through the end of the handle and holds the members 11 and 12 in their proper relation. The dowel pin can be withdrawn by springing the members 55 10 and 11 apart, which permits the two

halves of the holder to rotate on the rivet 15 in scissors fashion, for cleansing purposes.

At the end 12 I have provided a spring clamp 17 whose open end 18 crosses and 60 clamps against the outer sides of the ends 12 in grooves provided therein. The ends 19 of the clamp 17 are inturned and fit into small holes at the ends of the clamp grooves.

It can readily be seen that pressure applied to the ring-shaped handle of the clamp 65 17 will cause the inturned ends 19 to separate and to be disengaged from the ends 12, thereby permitting the ends 12 to spring apart and allow the introduction or the withdrawal of a blade.

The operation of my device is as follows: When desiring to sharpen a blade the clamp 75 17 is removed, as above described, and the blade inserted into the hole, as shown in Figure 1 or 4, depending upon the type of blade being sharpened. The clamp 17 is now replaced and the holder, with the blade 14 or 14^A, are applied to the strop in the same manner as would be an ordinary stiff-backed razor until the desired edge is obtained.

It is evident that other forms of fasteners may be employed to take the place of the clamp 17, the rivet 15 and the dowel pin 16 85 without departing from the spirit of my invention.

I am aware that many forms of holders have been constructed for safety razor blades. I therefore do not expect to cover 90 such devices broadly but I do intend to cover all such forms and modifications thereof as fall fairly within the appended claim.

I claim:

A holder for razor blades having, in combination, a somewhat elliptical elongated frame constructed of wood and split along its major axis; a pivot joining the halves of said frame near its middle separating the handle end from its blade holding end; a fastener at the extreme end of said handle portion; and a spring clamp at the extreme end of its blade holding portion, said clamp consisting of a wire ring whose ends intersect and turn parallel along side of said holder and the tips of whose ends turn inwardly and engage holes formed in the outer sides of the blade holding end of said frame.

EDGAR H. LUSHER.
